(57) CLAIM

What is claimed is the ornamental design for a document bag with strap, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view showing the document bag with strap of Applicant's invention.

FIG. 2 is a back view of the document bag with strap of Applicant's invention.

FIG. 3 is a left side view of the document bag with strap of Applicant's invention.

FIG. 4 is a right side view of the document bag with strap of Applicant's invention.

FIG. 5 is a top view of the document bag with strap of Applicant's invention; and,

FIG. 6 is a bottom perspective view of the document bag with strap of Applicant's invention.
